UNITED STATES PATENT OFFICE

JOHN M. FRANK AND STANLEY STACK, OF CHICAGO, ILLINOIS, ASSIGNORS TO ILG ELECTRIC VENTILATING COMPANY, OF CHICAGO, ILLINOIS, A CORPORATION OF LOUISIANA

CABINET AIR HEATER

Application filed August 8, 1929. Serial No. 384,345.

This invention relates to unit air heaters more especially designed for house heating, but of course capable of general application.

A somewhat recent type of heating unit 5 that has been designed with a view to economy of space in small rooms consists of a cabinet which fits into and occupies a recess in a wall of the room to be heated thereby. The front of the cabinet is substantially flush with the surface of the wall, and the openings in 10 the front of the cabinet through which the air is drawn into and expelled from the cabinet, are covered by an ornamental grill. Within the cabinet is mounted an air heating 15 element, such as a steam coil or radiator, and an air moving device, such as an electric fan, which draws air in through the lower opening, propels it upwardly over the heater, and expels it through the upper opening into the 20 room; all the parts except the front wall or cover of the cabinet being concealed from view and occupying none of the space of the room.

Our present invention relates to this general type of air heater, whether located in a wall recess or in the room itself, and has for its general object to improve the construction and enhance the desirability and efficiency of the unit. Other more specific objects are, to 25 provide a construction that may be adjusted to varying heights and widths, to provide an arrangement wherein the air will be drawn, instead of pushed, upwardly over the heater, to provide in the cabinet one or more side 30 passages that will allow the warm air to flow out through the natural chimney effect unobstructed by the fan and motor when the latter may be idle, and will also prevent short circuiting of the air by the fan and motor 35 and cause the air to be siphoned out of the side passage or passages by the partial vacuum created by the fan in front of said passage or passages, to provide improved means for humidifying the air, to provide improved 40 means for filling the humidifier, and to provide improved means for preventing over-heating of the fan motor.

Still further objects and attendant advantages of the invention will be apparent to those skilled in the art as the same becomes better

understood by reference to the following detailed description taken in connection with the accompanying drawings wherein we have illustrated an approved embodiment of the invention and in which—

Fig. 1 is a front elevation, showing the cabinet heater mounted in a recess in a wall. 55

Fig. 2 is an edge elevation, viewed from the right of Fig. 1, and partly in central vertical section. 60

Fig. 3 is a front elevation of the upper portion of the cabinet with the grill plates removed to show the interior construction. 65

Fig. 4 is a horizontal section on the line 4—4 of Fig. 1.

Fig. 5 is a top plan view, broken out, of a 70 sectional horizontal frame bar employed in the front wall of the cabinet.

Fig. 6 is an enlarged sectional detail on the line 6—6 of Fig. 5.

Fig. 7 is an enlarged sectional detail on the line 7—7 of Fig. 1. 75

Fig. 8 is an enlarged sectional detail on the line 8—8 of Fig. 1.

Fig. 9 is a perspective elevation showing the horizontally adjustable sectional units of the upper section of the cabinet in separated position. 80

In the drawings I have illustrated the cabinet heater as occupying a vertical recess 10 in the wall 11 of a room, but, as previously stated, its use is not limited to such location. With a view to reducing factory cost, I have herein shown the cabinet as constructed in a number of relatively slidable sections which are adjustable both horizontally and vertically so as to enable the cabinet to be assembled in varying heights and widths as ordered for corresponding heights and widths of wall recesses, or available wall space within a room. 85 For purposes of illustration, I have shown the cabinet in four vertical sections, the lower three of which are vertically adjustable relatively to each other, and in three horizontally adjustable sections; but, of course, the 90 number of sections employed is immaterial. 95

The uppermost section, in which the fan and fan motor are housed, comprises a central section 12 and duplicate end sections 13, these sections having the forms clearly illustrated 100

in Fig. 9, the central section 12 comprising a back wall 14, a top wall 15, and a depending front flange 16, and each of the end sections 13 comprising a back wall 17, a top wall 18, a vertical side wall 19, and flanges 20 and 21 on the front edges of the top and side walls 18 and 19, respectively. The inner ends of the end sections 13 are telescopicable within the ends of the intermediate section 12, as clearly shown in Fig. 3, and the sections may be secured together by bolts or rivets passed through holes 22 and 23 in the end sections registering with any of a series of holes 24 and 25 in the intermediate section. Secured to and depending from the flange 16 of the intermediate section 12 are a pair of spaced T-bars 26, and attached to the latter and to the rear wall 14 of the intermediate section are a pair of transverse partition plates 27, the purpose of which will appear later.

Located next below the topmost section of the cabinet last described is a section comprising a pair of end sections 28 of horizontal U-shape in cross section, and front and rear flat intermediate plates 29. The end sections 28 and the intermediate plate sections 29 are provided with cooperating bolt or rivet holes 30 and 31 respectively, by which said sections 30 may be assembled in varying widths. Extending across the upper edges of the sections 28 and 29 and behind the latter is the frame bar of T-shape illustrated in detail in Figs. 5 and 6, and comprising end and intermediate telescoping sections 32 and 33 respectively, that are formed with bolt or rivet holes 34 and 35, respectively, by which said frame bar may be assembled in varying lengths. A similar lengthwise adjustable frame bar designated as an entirety by 36, and shown in Fig. 2, is located on the inner side of the rear wall of the cabinet, and the lower edges of the rear walls of the top sections 12 and 13 are attached to the frame bar 36, while the upper edges of the sections 28 and 29 are similarly attached to both of the frame bars.

Next underlying the cabinet section comprising the units 28 and 29 is a similar section comprising similar end and intermediate units 37 and 38 respectively (see Fig. 4) which are adjustable width-wise of the cabinet with the same means and in the same manner as the sections 28 and 29. These sections are also as a whole vertically adjustable relatively to the superposed sections by means of rivet or bolt holes 39 cooperating with the rivet or bolt holes 30 and 31.

The lowermost sectional unit of the cabinet comprises end and intermediate sections 40 and 41 respectively, in all respect similar to the sections 28 and 29 and 37 and 38; the sections 40 being adjustable width-wise of the cabinet by means of cooperating bolt or rivet holes 42 and 43 in the sections 40 and

41, respectively, and also being vertically adjustable relatively to the next upper sections 37 and 38 through the provision of bolt or rivet holes 44 in the sections 37 cooperating with the holes 42 in the sections 40.

The transverse walls of the vertically telescoping sections 28, 37 and 40 may also be provided with vertically spaced cooperating bolt or rivet holes, by which said walls may be united at varying relative heights.

At points where the walls 40, 41, 37 and 38 all overlap each other there are, of course, four lapping thicknesses of metal; as is illustrated in the sectional views Figs. 7 and 8; but since the sheet metal employed is thin and flexible, the lapping portions are readily bent so as to avoid any appreciable air gaps or cracks between the overlapping plates in the vicinity of the quadruple lapped joints.

The front walls of the sections 40 are cut away throughout their lower portions, and the intermediate front plate 41 is similarly shortened, thereby producing in the front wall of the casing a lower opening designated as an entirety by 45, that is covered by a grill plate 46. The omission of front walls on the topmost sections 12 and 13 creates a transversely extending upper opening designated as an entirety by 47 in the cabinet, which opening is covered by an intermediate grill plate 48 and end grill plates 49. The grill plates 49 are attached at their upper edges to the flanges 16 and 20 of the top sections 12 and 13, and at their lower edges to the frame bar 33. The intermediate grill plate 48 is hinged, as shown at 50 in Fig. 1, to the adjacent vertical edge of one of the grill plates 49, so as to be capable of swinging outwardly.

Mounted on the rear side of the central grill plate 48 is a propeller fan 51 and an electric motor 52 for driving the same; the fan and motor being supported by tubular arms 53, the outer ends of said arms being attached to the grill plate 48. The inner ends of the tubular arms 53 communicate with the interior of a hood or casing in which the motor is mounted, so that the suction effect of the fan induces streams of cooling air through the tubular arm 53, thus keeping the parts of the motor cool. The grill plate 48 is normally maintained closed by a suitable latch and latch handle, indicated at 54, and by releasing the latter and opening the grill plate, the fan and motor may be swung outwardly with the latter into convenient position for inspection, oiling and repairs, when necessary.

Mounted in and extending across the lowermost section of the cabinet, preferably just above the lower opening 45 is an air heater in the form of a steam coil 55 equipped with steam supply and exhaust pipes 56 and 57, respectively.

Against the rear wall 41 and supported on a bracket 58 (Fig. 2) is a water pan 59 for humidifying the air, which water pan may

be readily filled through a funnel 60, the upper end of which may be attached to the frame bar member 33, said funnel having a long neck 61 extending into the water pan 59. By opening the center panel 48, the pan 59 may be readily filled when required through the funnel.

The action of the apparatus is readily understandable from the foregoing description 10 of its structure, but may be briefly outlined as follows.

With steam turned into the heating coil 55, and the fan 51 started in operation, the cooler air at the bottom of the room is sucked 15 through the lower opening 45, upwardly over the heater 55 by which its temperature is raised, thence upwardly through the cabinet, and out through the central fan chamber behind the upper opening 47 and through the 20 latter. The partial vacuum created on either side of the fan in front of the grill 49 also sets up an induced current through the side portions of the cabinet; and the presence of the transverse partitions 27 which define 25 the side walls of the fan chamber prevents the creation of local air currents or short circuits through the side grills 49 to the rear of the fan, and thus limits the entire air circulation to a flow from the bottom to the top of 30 the cabinet. In warm weather when it may be desirable merely to effect a circulation of the air in the room, the heating medium is, of course, cut off from the heater 55.

The described sectional character of the 35 cabinet, by which it may be assembled at the factory in varying heights and widths is an important and advantageous feature from a manufacturing standpoint, since it renders unnecessary the building of complete cabinets in a number of different sizes, enabling the different sizes to be assembled from uniform stock sizes of parts, all of which, with the exception of the grill plates 49 and 46, may be of fixed and uniform sizes. The 40 structural details herein disclosed may, of course, be widely varied without departing from the substance of the invention, or sacrificing any of the advantages thereof, and thence I do not limit the invention to the 45 specific structure disclosed, except to the extent clearly indicated in specific claims, but reserve all such variations, modifications and mechanical equivalents as fall within the 50 spirit and purview of the claims.

55 We claim:

1. In a cabinet air heater, the combination of an upright cabinet formed with upper and lower openings in its front wall, a heating element mounted in said cabinet, a 60 fan and fan motor mounted in said cabinet opposite said upper opening and of less width than the latter, and a transverse partition in said cabinet at one side of said fan and motor, said partition extending across said 65 upper opening.

2. In a cabinet air heater, the combination of an upright cabinet formed with upper and lower openings in its front wall, a heating element mounted in said cabinet, a fan and fan motor mounted in said cabinet 70 opposite said upper opening and substantially midwidth of the latter, and transverse partitions in said cabinet at the respective sides of said fan and motor, said partitions extending across said upper opening. 75

3. In an air circulating device, the combination of an upright cabinet formed with upper and lower openings in its front wall, a grill hinged to said front wall and normally covering said front opening, a fan and electric motor behind said grill, a hood in which said motor is mounted and tubular arms by which said motor is supported by said grill, said arms opening at one end through said grill and at their other ends 80 opening into said hood, and serving for the introduction of cooling air to the motor under the suction effect of the fan.

4. In an air circulating device, the combination of an upright cabinet formed of 90 sections vertically adjustable relatively to each other to vary the height of said cabinet, the front wall of said cabinet having upper and lower openings, and a fan and fan motor mounted in said cabinet and operating to move air through said lower opening and expel the same through said upper opening. 95

5. In an air circulating device, the combination of an upright cabinet formed of lapping sections both vertically and horizontally adjustable relatively to each other whereby to vary the height and width of said cabinet, the front wall of said cabinet having upper and lower openings, and a fan and 100 fan motor mounted in said cabinet and operating to move air through said lower opening and expel the same through said upper opening. 105

6. In a device for circulating and humidifying air, the combination of an upright cabinet formed with upper and lower openings in its front wall, a water pan mounted in said cabinet between said openings, a filling tube for said pan extending from said 110 upper opening downwardly into said pan, and a fan and fan motor mounted in said cabinet opposite said upper opening and operating to draw air through said lower opening and over said water holder, and expel 115 the same through said upper opening.

7. In a cabinet air heater and humidifier of the type described, the combination of an upright cabinet formed with upper and lower openings in its front wall, a heating 120 element mounted in said cabinet above said lower opening, a water pan mounted in said cabinet above said heating element, and a fan and fan motor mounted in said cabinet behind said upper opening and operating to 125 130

draw air through said lower opening over said heating element and water pan, and expel the same through said upper opening.

8. In a cabinet air heater and humidifier of the type described, the combination of an upright cabinet formed with upper and lower openings in its front wall, a heating element mounted in said cabinet above said lower opening, a water pan mounted in said cabinet above said heating element, a filling tube for said pan extending from said upper opening downwardly into said pan, and a fan and fan motor mounted in said cabinet behind said upper opening and operating to draw air through said lower opening over said heating element and water pan, and expel the same through said upper opening.

9. In a cabinet air heater and humidifier of the type described, the combination of an upright cabinet formed with upper and lower openings in its front wall, a hinged grill covering said upper opening, a heating element mounted in said cabinet above said lower opening, a water pan mounted in said cabinet above said heating element, a filling tube for said pan extending from said upper opening downwardly into said pan, and a fan and fan motor mounted on the rear side of said hinged grill and operating to draw air through said lower opening over said heating element and water pan, and expel the same through said upper opening and grill.
